UNITED STATES PATENT OFFICE

LOUIS C. HOBART, OF AVALON, PENNSYLVANIA, ASSIGNOR TO GEM MANUFACTURING COMPANY, A CORPORATION OF PENNSYLVANIA

CHAPLET MAKING MACHINE

Application filed April 15, 1929. Serial No. 355,014.

This invention relates to chaplet making machines, more particularly to apparatus for forming sheet metal members and securing said members on the end of a wire for use as core supports in foundry work.

It is among the objects of this invention to provide apparatus of the above designated character which shall be adapted to feed a sheet metal strip to a perforating punch, perforate the strip, cut-off a predetermined length and transfer same to a conveyor wheel, feed wire to a scoring die, cut-off member and holding jig, scarfing the end of the cut-off wire, assembling the perforated sheet member on the end of the wire, and riveting the end of the wire to secure the sheet member thereon, all in a continuous operation.

It is another object of the invention to improve and simplify the operating mechanism of chaplet making machines to substantially increase their quantity output.

These and other objects will become more apparent from a consideration of the accompanying drawings, constituting a part hereof, in which like reference characters designate like parts and in which Figure 1 is a front elevational view of a machine embodying the principles of this invention; Figure 2 a top plan view thereof with the punch mechanism removed; Figure 3 an enlarged sectional elevational view of the principal operating mechanism; Figure 4 a sectional elevational view taken along the line IV-IV, Fig. 1; Fig. 5 an end view diagrammatically illustrating cam and indexing mechanism; Figure 6 a sectional elevational view taken along the line VI-VI, Fig. 1; Figure 7 a detail view in front elevation of a jig wheel; Figure 8 a similar view of a conveyor wheel and ratchet mechanism; Figure 9 a detail view in elevation of a wire cutting mechanism; and Figures 10 and 11 a top plan and side elevational view respectively of a chaplet produced by the apparatus.

Referring to Figures 1 and 2 of the drawings, the structure therein illustrated comprises a rectangular frame structure 1 supported on pedestals 2 having a shaft 3 journaled centrally in said frame. A pair of

their axes disposed transversely of the longitudinal axis of shaft 3. A main drive shaft 5 is journaled in brackets 6 and 7 at the rear of frame 1 and connected by gearing 8 and 9 to actuate shafts 4. As shown in Figure 4 a cam shaft 10 is journaled for rotation with its axis in parallel alignment with shaft 5 and below the latter, the camshaft being actuated through a geared connection 11 with shaft 5.

Mounted on one end of frame 1 is a vertically extending punch head 12 in which a ram 13 is mounted for reciprocating movement in guideways 14 which movement is effected by a pitman 15 operated by a crank shaft 16 which is geared by wheels 17 and 18 to a shaft 19 operated through geared connections at 20 by drive shaft 5. On crank shaft 16 are mounted cams 21, 22, 23, 24 and 25, Figure 4, operating levers hereinafter described. Ram 13 is provided with a perforating punch 26 and a shear 27, Figure 3, which cooperate with a combined die and shear block 28. Ram 13 is further provided with a cut-out portion 29, Figure 4, in which is slidably mounted a block 30 carrying a finger 31 movable in a guide 32. A lever 33 is mounted for oscillating movement in a bracket 34 below die-block 28, the crank being connected by a link 35 to a bell crank 36 carrying a cam follower 37, a finger 38 is connected through a universal joint 39 to the end of lever 33 for movement in a guide 40, finger 38 being coaxially aligned with finger 31 to cooperate therewith.

A bracket 41 extends beyond die block 28 and is provided with an inclined end for journaling a transfer dial 42, Figures 1, 3 and 8.

Wheel 42 is provided with spring fingers 43 in angularly spaced relation which are integral with or mounted on a flared or dished portion 44 of the wheel. As shown in Figure 8, a lever 45 is mounted on a stud shaft 46 on which dial 42 is journaled. Lever 45 is movable independently of dial 42 by a link 47 with which is it pivotally connected at 48, link 47 being pivoted at 49 to a crank lever 50 actuated by cam 25. A pawl 51 is carried by lever 45 and rests on stop 52 against which it is biased by a spring 53. In this position it successively engages the pins 54

projecting on dial 42 and for every movement of lever 45 wheel 42 is indexed one position corresponding to the angular spacing of fingers 43, there being a pin 54 for each pair of fingers 43 of the wheel.

Sheet metal strip material is fed to the punch and die by the following mechanism: A guide 56 is provided at the material feeding end of the machine. A gripper block 57 is mounted on a guideway 58 the block being movable through a segment gear 59 mounted on a rocker shaft 60 which is oscillated by a lever 61 having a link connection 62 with a lever 63 that is connected at one end with a link 64. Link 64 is pivotally connected to a T-bolt 65 which is movable in the slot 66 of a rocker 67 that is loosely mounted on shaft 16 and rocked by a cam follower 68 actuated by cam 21. The position of bolt 65 in slot 66 determines the swing of segment gear 59 and consequently the length of travel of block 57. Mounted on the latter is a lever 70 pivoted at 71 and carrying a roller 72. Lever 70 and block 57 are provided with grippers 73 for engaging a strip 74 which is fed to the punch. A lever 75 is pivoted at 76 and connected by a link 77 to a lever 78 having a cam follower 79 actuated by cam 22. Lever 75 engages roller 72 of lever 70 whereby the strip material 74 is firmly engaged by grippers 73 in response to cam 22. Movement of lever 75 is limited by stop 80 which is adjustable for the different gauge or thickness of the strip material 74.

Underneath the mechanism for feeding strip material 74 is a wire feed and scoring device which consists of the following mechanism: A guide block 81 movable through a segment gear 82 mounted on a rocking shaft 83 which is actuated through a lever and link connection 84 and 85 respectively by a lever 86 which is oscillated by a cam follower 87 which engages a cam 88 mounted on shaft 4. Link 85 is adjustably connected in a slot 89 of lever 86 to vary the swing of gear 82 to vary the rate of feeding the wire 90. Adjacent the feed mechanism just described is a scoring device 91 having cutters which engage and disengage wire 90 to notch or score it as at 91', Fig. 11, responsive to oscillating movement of member 91 effected through lever 92 by a cam of shaft 10 at the rear of the machine. A second scoring device 93 is mounted adjacent member 91, the cutters 94 of which are shown in Figure 1. This member is oscillated through linkage 95 operated by a cam on shaft 10, and the depth of the scoring in wire 90 may be adjusted by means of set screws 96 whereby links 92 and 95 are lengthened or shortened as desired to vary depth of the cut.

In longitudinally spaced relation with the scoring member 93 is a wire cutter 97 functioning as a shear through the relative movement of the members 98 and 99, the latter

being shown in detail in Figure 9. The member 99 is actuated through a lever 100 having a cam follower 101 in engagement with a cam 102 on shaft 10. The cutter 99 is adjustably connected through stop 103 and adjustable 70 seat 104.

Cooperating with the wire cutter 99 and conveyor wheel 42 is a rotatable jig 105, Figure 7, mounted on the end of shaft 3. The jig is provided with angularly spaced radial slots 106 corresponding in spacing and number to the pairs of fingers 43 of wheel 42. Die blocks 107 are permanently secured to the disk 105 by screws 108 and movable blocks 109 are disposed in the slots to cooperate with blocks 107, said movable and stationary blocks being notched at their engaging faces at 110 to form grippers for holding the wire after it is cut. Movable blocks 109 are retained in the disk by a bottom support 111, Figures 1 and 3, and a brake 112 is adapted to engage blocks 109 at their top position on disk 105, the blocks being made to protrude slightly beyond the periphery of disk 105 when in engagement with blocks 107. Brake 112 is pivotally connected at 113 to a pivot block 114 fastened to the side frame 1 and at its other end it is pivoted at 115 to a link 116 which is connected to a lever 117 actuated by cam 118 of shaft 10 through follower 119. Brake 112 is provided with adjustable dogs 120 for engaging the ends of blocks 109 which are slightly rounded for this purpose.

Between the strip feed and punching and the wire feed and cutting mechanisms is a ram 121 movable longitudinally in a guide 122 the ram being pivotally connected at 123 to a pitman 124 mounted on a crank 125 of shaft 4. Ram 121 carries a plurality of dies 126, 127 and 128 in spaced relation as shown in Figure 4, corresponding to the spacing of openings 110 of wire jig 105. The member 126 is adapted to scarf the end of the cut off wire 90 to form a shoulder 129, Figure 11. Member 127 is provided with a pin 130 which engages the perforations of the cut-off strip material to transfer the same from the fingers 43 of conveyor wheel 42 to the scarfed end of wire 90 as shown in Figure 11, pin 130 being movable and recedes when the wire held in jig 105 enters the perforation of the material 131 being transferred. Member 128 rivets the end of the wire after member 131 has been assembled thereon thus completing the chapter which is subsequently pushed out of jig 105 by a finger 132 secured to a rod 133. Rod 133 is subjected to longitudinal movement and is timed by a cam 134 on shaft 10.

The jig plate 105 is indexed and timed with conveyor wheel 42 by means of the following mechanism: Referring to Figure 5 of the drawings, shaft 3 is provided with a disk 136 having notches 137 adapted for engagement by pawls 138 and 139. Pawl 138 is provided with a roller 140 movable in a slot 141 of an

arm 142 which holds it in operative position. Pawl 138 is pivoted at 143 to lever 144 having a cam follower 145 engaging a cam 146 which is rotatable through shaft 147 actuated by gear wheels 148 and 149 from drive shaft 5.

5 Pawl 139 is operated through lever 150 having a cam follower 151 engaging cam 152 also rotatable with shaft 147. Through movement of the pawls, the notched disk is subjected to angular movement to rotate shaft 3 and jig plate 105 at the end thereof, the amount of angular movement producing proper indexing of jig 105 to bring openings 110 in proper alignment with the wire feed 15 and members 126, 127 and 128.

The operation of the chaplet making machine is briefly as follows: Strip material 74 of sheet metal in width corresponding to the size of the chaplet to be made and of any 20 suitable thickness or gauge, is fed from a supply reel through guide 56 and passed between gripping jaws 73 to the die block 28. Wire of suitable gauge is passed through feed mechanism 81 and the scoring devices 91 and 25 93 into cut-off 97. The drive shaft 5 is connected to a suitable prime mover such as an electric motor and the drive pulley is preferably connected to shaft 5 through a clutch mechanism 5a. When the clutch is engaged, shaft 5 rotates and the foregoing described mechanism is actuated whereby the following sequence of operations occurs. The perforating die 26 pierces a hole in strip 74 and upon the subsequent advance of the strip feeding 30 mechanism, which is set by adjustment of link 64, in slot 66 of the cam operated rocket 67 to advance a distance corresponding to the width of the strip, the shear 27 will cut-off a rectangular or square portion of sheet 35 40 metal having a perforation in the center thereof. As the strip material is sheared, it is engaged by fingers 31 and 38 and placed between spring fingers 43 of transfer dial 42 and by the cam operated movement of lever 45 which is timed with the reciprocating 45 movement of the punch ram 13, the dial 42 is indexed to advance a distance equal to the spacing of fingers 43 for each stroke of the punch.

50 Simultaneously with the perforating, shearing, and transferring of the sheet strip material wire 90 is fed by mechanism 81 through scoring mechanism 91 and 93 and the cut-off 99 to the jig plate 105 in which the pieces cut off to suitable length, are inserted in openings 110 in blocks 107 and 109. When 55 jig 105 is indexed one position as heretofore explained, the cut off wire is acted upon by the scarfing member 126 which is advanced to engagement with the end of the wire by movement of ram 121. Member 126 produces the shoulder 129 on the wire shown in Figure 11, and upon the movement of jig 105 to its next indexed position, the member 127 60 will engage a perforated punching 131 and

place it on the scarfed end of wire 90. Upon the subsequent indexing of the jig the assembled wire and punching will be aligned with the riveter 128 which acts upon the end of the wire to securely fasten them. 70

During the operation of scarfing, assembling and riveting, brake 112 is depressed by its cam to lock the slide blocks 109 in the jig and the latter is likewise secured against movement by action of the brake. When the riveted chaplets reach the lower position in the jig slide blocks 109, drop by action of gravity against the retaining member 111 and the rod 133 presses fingers 132 against wire 90, forcing chaplet out of jig from which it drops into a container placed below the jig. 80

The speed of operation is dependent upon the accurate setting of the machine and the securing of the jig plate when the several operations terminating in the riveting of the 85 chaplets occurs.

The brake makes possible high speed operation as it effectively holds the jig plate against movement which would cause jamming of the machine. 90

The strip feed, perforating and shearing operations, as well as the wire feed, scoring and cutting operations, are coordinated by the cam movements as explained and the indexing of conveyor dial 42 and jig plate 105 is 95 coordinated with movement of ram 121 by their respective cam and ratchet mechanisms. All movable parts of the machine are actuated by a common drive shaft which guards against any parts of the machine getting out 100 of time.

It is evident from the foregoing description of this invention that apparatus made in accordance therewith provides efficient means for the manufacture of chaplets in production quantities and at minimum cost. 105

Although one embodiment of the invention has been herein illustrated and described, it will be obvious to those skilled in the art that modifications may be made in the details of construction and in the arrangement of the several cooperating parts without departing from the principles herein set forth. 110

I claim herein as my invention:

1. In a chaplet machine the combination of 115 a reciprocating punch and means for feeding strip material thereto, wire scoring and cutting members and means for feeding wire thereto, a jig for receiving the cut off wire lengths, a transfer dial for receiving the strip punchings, means for forming a shoulder on the wire in the jig, means for transferring the strip punchings from said dial to the wire in said jig and means for fastening the punchings on the ends of the wire. 120

2. In a chaplet machine the combination of 125 a reciprocating punch and means for feeding strip material thereto, wire scoring and cutting members and means for feeding wire thereto, a transfer dial for receiving the strip 130

5 punchings, a jig for receiving the cut off wire, a reciprocating ram having dies in co-operative alinement with the wire in said jig, means for indexing said dial and jig and for coordinating the movements thereof and means for subjecting said ram to reciprocatory movement in synchronism with the indexing movements of said jig.

10 3. In a chaplet machine the combination of a reciprocating punch and means for feeding strip material thereto, wire scoring and cutting members and means for feeding wire thereto, a transfer dial, means on said dial for yieldingly engaging the strip punchings, 15 a jig for receiving the cut off wire, said conveyor and jig being arranged so that the holding means of the dial are in alinement with the wire holding means of the jig, and means for transferring the punchings from said dial to the end of the wire in said jig.

20 4. In a chaplet machine the combination of a reciprocating punch and means for feeding strip material thereto, wire scoring and cutting members and means for feeding wire thereto, a transfer dial, means on said dial for yieldingly engaging the strip punchings, 25 means for engaging the punchings and placing them in the holding means of said dial, a jig for receiving the cut off wire, said dial and jig being arranged so that the holding means of the wheel are in alinement with the wire holding means of the jig, and means for transferring the punchings from said wheel to the end of the wire in said jig.

30 5. In a chaplet machine the combination of a reciprocating punch and means for feeding strip material thereto, wire scoring and cutting members and means for feeding wire thereto, a transfer dial, means on said dial for 35 yieldingly engaging the strip punchings, a jig for receiving the cut off wire, said dial and jig being arranged so that the holding means of the wheel are in alinement with the wire holding means of the jig, and means for 40 transferring the punchings from said dial to the end of the wire in said jig, and means for indexing said dial and jig and for coordinating the indexing movements.

45 In testimony whereof I have hereunto set
50 my hand this 4th day of April, 1929, at South-
ington, Connecticut.

LOUIS C. HOBART.
